UNITED STATES PATENT OFFICE.

WILLIAM S. GUBELMANN, OF BUFFALO, NEW YORK.

HORIZONTAL RULING MECHANISM FOR CALCULATING AND LIKE MACHINES.

1,233,307

Specification of Letters Patent.

Patented Mar. 9, 1920.

Original application filed January 10, 1900, Serial No. 1,004. Divided and this application filed July 12, 1918. Serial No. 244,575.

To all whom it may concern:

Be it known that I, WILLIAM S. GUBELMANN, a citizen of the United States, residing in Buffalo, in the county of Erie and State of New York, have invented certain new and useful Improvements in Horizontal Ruling Mechanisms for Calculating and like Machines, of which the following is a specification.

10 This invention relates to improvements in horizontal ruling mechanism for calculating and like machines and is a division of my pending application Serial No. 1,004, filed Jan. 10, 1900.

15 Only such of the mechanism herein described as refers to horizontal ruling mechanism is claimed herein.

In the original application 1,004 filed Jan. 10, 1900, is claimed grand total mechanism and combinations therewith.

20 The following is a list of the divisions of said parent application 1,004, and the subjects matter claimed in each.

25 Serial No. 183,397, filed July 30, 1917, general combinations of all the mechanism of the machine, exclusive of the grand total mechanism and not falling more particularly under one of the other divisions.

30 Serial No. 183,398, filed July 30, 1917, general combinations drawn to a simple adding machine.

Serial No. 254,065, filed Sept. 14, 1918, ribbon feeding and reversing mechanism.

35 Serial No. 123,842, filed Oct. 5, 1916, printing mechanism.

Serial No. 130,583, filed Nov. 10, 1916, key mechanism.

Serial No. 251,476, filed Aug. 26, 1918, counting mechanism.

40 Serial No. 257,465, filed Oct. 9, 1918, numbering mechanism.

Serial No. 264,629, filed Nov. 27, 1918, mechanism for transforming an adding and listing machine into a counting and numbering machine.

45 Serial No. 245,336, filed July 17, 1918, vertical ruling mechanism.

Serial No. 258,051, filed Oct. 14, 1918, split calculating machine.

50 Serial No. 242,395, filed June 28, 1918, carriage mechanism.

Serial No. 246,158, filed July 22, 1918, non-print mechanism.

55 Serial No. 248,127, filed Aug. 3, 1918, eliminating mechanism.

Serial No. 249,303, filed Aug. 10, 1918, repeating mechanism.

Serial No. 260,030, filed Oct. 28, 1918, carriage mechanism.

Serial No. 261,806, filed Nov. 9, 1918, 60 distinguishing means for the keys and dials.

Serial No. 249,905, filed Aug. 14, 1918, key interlocking mechanism.

Serial No. 243,444, filed July 5, 1918, 65 paper supporting means.

Serial No. 250,536, filed Aug. 19, 1918, 70 duplicate printing mechanism.

Serial No. 251,778, filed Aug. 28, 1918, word printing mechanism.

Serial No. 256,263, filed Sept. 30, 1918, 75 dating mechanism.

One of the objects of the invention is to provide improved means for ruling horizontal lines in calculating and like machines.

Another object is to provide the regular 75 number type carriers with horizontal rule types and to provide means for operating all of said carriers to present their rule types to the printing position and to take a printing impression therefrom.

80 Another object is to provide machines having a plurality of unrelated sets of types for simultaneously printing separate and distinct items, with means which by a single manipulation will effect ruling under items 85 printed by a plurality of such sets of types.

Another object is to provide a horizontally movable paper carriage so that ruling may be done in different horizontal positions of the sheet, whereby a continuous horizontal line can be printed across the sheet.

90 Another object is to provide means whereby when the ruling is rendered operative, the adding is automatically rendered inoperative.

95 Another object is to provide means whereby sets of types ordinarily operable to print items in duplicate may be controlled to print horizontal ruling.

100 Another object is to provide word printing mechanism with a horizontal ruling device automatically operable upon operating the horizontal ruling mechanism of the number printing mechanism.

105 In the accompanying drawings consisting of seven sheets:

Figure 1 is a fragmentary top plan view of my improved adding and recording machine.

110 Fig. 2, is a vertical longitudinal section

of the same, taken substantially in line 2—2, Fig. 1, and showing the adding and recording mechanism of one column or set of keys in the normal or inoperative position.

5 Fig. 3 is a fragmentary sectional elevation of the printing mechanism of one of the rows of keys, viewed from the side opposite to that shown in Fig. 2.

10 Fig. 4 is a fragmentary sectional elevation taken in line 4—4, Fig. 1, and showing the devices whereby numbers are printed in duplicate.

Fig. 5 is a horizontal section taken in line 5—5, Fig. 3.

15 Fig. 6 is a vertical section in line 6—6, Fig. 3.

20 Fig. 7 is a view similar to Fig. 2, with the paper carrying device omitted and showing the parts of the adding and recording mechanism in a shifted position.

25 Fig. 8 is a fragmentary longitudinal sectional elevation taken substantially in line 8—8, Fig. 1, and showing the mechanism whereby words are printed.

30 Fig. 9 is a fragmentary longitudinal sectional elevation taken substantially in line 9—9, Fig. 1, and showing the auxiliary registering and recording mechanism.

35 Fig. 10 is a fragmentary sectional side elevation of one of the printing segments showing the means for mounting the type movably thereon.

40 Fig. 11 is a cross section of the type segment taken in line 11—11, Fig. 10.

45 Fig. 12 is a side view of one of the type carriers viewed from the side opposite to that shown in Fig. 10.

50 Fig. 13 is a perspective view of one of a pair of substantially similar cams, one of which serves to shift the dial operating segments into their operative position and the other one of which serves to shift the parts into position for printing a total of the added numbers.

55 Fig. 14 is a fragmentary perspective view of the hammer operating mechanism.

60 Fig. 15 is a longitudinal sectional elevation, taken substantially in line 15—15, Fig. 1, and showing particularly the paper carriage and the mechanism whereby different parts of the machine may be thrown into and out of gear.

65 Fig. 16 is a fragmentary perspective view showing the key lever, the main gear segment, the controlling arms and the printing segment of one of the higher columns of numbers.

70 Fig. 17 is a vertical section taken substantially in line 17—17, Fig. 2.

75 Fig. 18 is a fragmentary transverse section taken in line 18—18, Fig. 2, and showing the means for adjusting the paper carriage lengthwise of the line of printing.

80 Fig. 19 is a vertical transverse section taken in line 19—19, Fig. 2.

Fig. 20 is a fragmentary detail view of the horizontal rule types, and platen.

85 Fig. 21 is a detail view showing one of the yokes which connect the main and duplicate printing segments.

90 Fig. 22 is a fragmentary perspective view of the units gear segment and controlling arm of the main adding mechanism.

95 Like reference characters refer to like parts in the several figures.

General construction.

1 represents the main frame of the machine which may be of any suitable construction so as to support the working parts 80 of the machine.

2, Figs. 2, 7, and 9 represent a number of main dials which register the total of the numbers which are added together. These dials consist preferably of cup-shaped 85

wheels which are numbered on their periphery and are mounted in their proper order on a transverse dial shaft 3, which is journaled in bearings on the main frame, the dials being so arranged that the dial representing 90

the lowest number is arranged on the right hand end of the series and the dials representing the successively higher numbers being arranged successively in 95

their order toward the left from the dial representing the lowest number. The lowest or right hand dial is preferably divided on its periphery into eighths so as to indicate fractions of a cent in eighths, and the remaining dials are graduated on their 100

periphery according to the decimal system into tenths. As shown in the drawings ten 105

total dials are shown and extend from fractions of a cent to tens of millions, but if desired, additional dials may be added to the 110

right and to the left of the series, if it is desired to register smaller divisions of a cent or more than tens of millions. Each of 115

the main total dials 2 is provided on its left hand side with a gear pinion 4, which is rigidly connected therewith, as shown in Figs. 110

2, 7, and 9. The pinion of the fraction wheel has eight teeth while the pinions of the remaining dials are each provided with ten teeth. 5 represents the main registering 115

gear segments, one of which is provided for each of the dials 2 and is adapted to engage with the pinion thereof, for operating the respective dial. Each of these gear segments is arranged in rear of its companion 120

gear pinion and is provided at its lower end with a rearwardly projecting arm 6 which is pivoted loosely on a transverse supporting rod 7. This rod is mounted with its ends 125

on the upper ends of two rock arms 8 which turn loosely with their lower ends on a transverse rock-shaft 9. The rock-arms 8 are connected by a transverse bar 10 which 130

compels the two arms to move back and forth together. In the normal position of 130

the gear segments when the machine is at rest these segments are retracted rearwardly out of engagement with the dial pinions of the dials and the segments are elevated so that their lowermost teeth are opposite the spaces between the adjacent teeth of the dial pinions, these spaces being in line with the pivots of the pinions and the gear segments.

The gear segments are yieldingly held 10 backwardly out of engagement with the dial pinions by means of springs 11 connecting the rock arms 8 with a stationary part of the frame. Fig. 15 shows one of the springs 11 connecting one of the rock-arms 8 with a 15 transverse stationary bar 12 in the rear part of the machine. The gear segments are moved forwardly so that their teeth engage with the dial pinions 4 by means of a shifting rock-arm 13, which is preferably secured 20 to the right hand rock-arm 8 and projects rearwardly. Upon raising the shifting rock-arm 13, the rock arms 8 are swung forwardly and the gear segments 5 are engaged with the dial pinions, while upon swinging 25 the shifting rock-arms downwardly, the rock-arms 8 are swung rearwardly and the gear segments are disengaged from the dial pinions.

14 represents a cam whereby the gear segments are engaged with the dial pinions. This cam is mounted on the upper portion of a vertically swinging rocking frame 15 which is arranged on the right hand side of the machine. This cam is provided at its 35 front end with an incline or cam face 16 and at its rear end with a concentric face 17. When the cam is in its rearmost or retracted position, its incline stands in rear of a roller or projection 18 on the rear end of the shifting arm 13, as shown in Figs. 2, 7, 9 and 17. Upon swinging the rocking frame 15, so that the cam 14 moves forwardly, the incline of the latter engages underneath the roller 18 and raises the arm 13, thereby moving 40 the arms 8 forwardly. The throw of the incline 16 is just sufficient to engage the teeth of the gear segments with the dial pinions. When the roller 18 has been raised to the top of the incline, the concentric portion 45 of the cam engages with the roller during the continued forward movement of the cam and the latter does not shift the gear segments any farther forward.

When the rear end of the concentric face 55 17 of the cam passes forwardly from underneath the roller 18, the constant pull of the springs 11 causes the rock-arm 13 to be depressed and the rock-arms 8 to be moved rearward, thereby disengaging the gear segments from the dial pinions. Upon now 60 moving the cam 14 backwardly together with the rocking frame 15, this cam does not affect the arm 13 and the parts connected therewith, but is affected by said arm 65 at the last portion of the backward move-

ment of the cam, at which time the back or lower side of incline 16 engages with the roller 18 which lifts incline and at the end of the backward movement of the cam, the latter clears said roller and drops behind the same, as shown in Fig. 2, preparatory to again raising the roller 18 and connecting parts during the next forward movement of the cam 14.

For the purpose of permitting the front 75 end of the cam to rise so as to clear the roller 18, this cam is pivoted at its rear end, to the rear portion of the rocking frame 15. The upward and downward movement of the front end of the cam is limited by means 80 of a lug 19 projecting from the side of the cam and engaging with a slot in the adjacent part of the rocking frame 15, as shown in Fig. 17.

The rocking frame 15 is secured with its 85 lower portion to a transverse rock-shaft 20 journaled in the main frame and provided outside of the frame with a hand crank 21, as shown in Fig. 17, whereby this shaft is rocked and the parts connected therewith are 90 operated.

The gear segments 5 are raised to their highest position by means of a return or lifting bar 22 which extends transversely underneath all of the arms 6 of the gear 95 segments and which is connected loosely at its rear ends with the transverse rod 7 by lifting plates 23. 24 represents two shifting arms which are mounted loosely at their rear ends on the rock-shaft 20 and which 100 support at their other ends a transverse bar 25 which transverse bar is connected at its ends, by two links 26, with the lifting plates 23, whereby upon raising the shifting arms 24, the lifting bar 22 is caused to raise the 105 gear segments and the other parts connected therewith resting on said bar. Upon depressing the transverse bar 25, the lifting bar 22 is moved downwardly and the gear segments resting thereon are permitted to 110 move downwardly with the bar until the segments are arrested.

Each of the gear segments is yieldingly held in contact with the lifting bar 22 by a spring 27 which connects the arm of the 115 segment with the transverse bar 25. If the downward movement of the gear segment is arrested while the shifting arms 24 continue to move downwardly, the lifting bar 22 is moved away from the underside of the 120 arm of the gear segment and the spring 27 is strained. The transverse bar 25 is arranged at one end in a segmental notch 28 formed in the front part of the rocking frame 15, shown in Figs. 2, 7, 9 and 17, and its opposite end is arranged in a similar segmental notch 28, formed in a rocking frame 29 which is secured to the operating shaft on the left-hand side of the machine. The 125 rocking frames 15 and 29 together with the 130

operating shaft 20 constitute the main or universal operating frame of the machine.

- When the machine is at rest, as shown in Fig. 2, the transverse bar 25 engages with the front side of the notches 28 in the rocking frames 15 and 29. Upon turning the rocking shaft 20 forwardly by means of its handle 21 in the direction of the arrow, Fig. 2, the rocking frames are moved forwardly during the first part of the movement independent of the transverse bar 25. The latter remains at rest until the inclined front end 16 of the cam 14 has raised the arm 13 and moved the gear segments into engagement with the dial pinions, during which movement the rocking frames move idly the extent of their notches 28 along the ends of the bar 25 without disturbing the latter. After the gear segments have been engaged with the dial pinions, the continued forward movement of the rocking frames causes the rear ends of their notches 28 to engage with the bar 25 and depress the same, thereby causing the lifting bar 22 to be moved downwardly and strain the springs 27. This causes all of the gear segments which are free, to be moved downwardly and to continue their downward movement until they are arrested. During the downward movement of the gear segments, while they are in engagement with the dial pinions, the latter and the dials connected therewith are turned in the direction of the arrow, Fig. 7, until the downward movement of the segments is arrested. The extent which each dial is turned depends upon the position in which the downward movement of its operating segment is arrested. After the segments have been arrested in their downward movement, they remain in this position while the rocking frames complete their forward movement. At the end of the forward movement of the rocking frames, the roller 18 of the rock arm 13 drops off from the rear end of the concentric part of the cam 14, thereby allowing the springs 11 to pull the gear segments rearwardly out of engagement from the dial pinions.
- Upon now turning the rock-shaft 20 backwardly by means of the handle 21, the rocking frames are moved backwardly until the front ends of the notches engage with bar 25. When the latter is so engaged it is moved backwardly with the rocking frames to the end of their rearward movement which causes the transverse bar 25 to lift the lifting bar 22 and the gear segments which have been depressed, into their highest or normal position. During this upward movement of the depressed gear segments they are out of engagement with the dial pinions, so that the dials are not turned backwardly with the segments, but remain in their shifted position.
- 30 represents a number of elbow-shaped controlling arms which form part of the devices whereby the downward movement of the registering gear segments is controlled. One of these arms is arranged along the left-hand side of each gear segment and consists of an upright front part and a horizontal lower part which extends rearwardly from the lower end of the upright part, thereby leaving a clear space in rear of the upright part of the controlling lever as represented in Figs. 1, 2, 7, 9, and 16. The rear end of the lower part of each controlling arm is mounted loosely on a transverse supporting bar 31, while the upper end of its front or upright part is loosely connected with the upper portion of its companion gear segment. This loose connection permits the controlling arm and the gear segment to swing freely about their individual axes, which are arranged parallel but out of line, and also permits the gear segment to move forward and backward into and out of engagement with its companion dial pinion. In the uppermost position of the controlling arms the same bear with their upper ends against a transverse stop bar 32, as shown in Fig. 2, which limits the upward movement of these arms. Each controlling arm is provided on the rear part of its upper end with a locking lug 33, and on the front part of its upper end with a stop lug 34, both of which lugs project toward the left and are preferably stamped out of one piece with the controlling arm.
- The operation of the registering devices is controlled by a number of elbow-shaped key levers which are arranged side by side and pivoted to a transverse supporting rod 35. Each key lever is provided with a lower actuating arm 36 which projects forwardly and an upper stop arm 37 which projects upwardly along the left hand side of one of the controlling arms and gear segments, as represented in Figs. 2, 7 and 16. Each of these key-levers is provided on the rear side of its stop arm with a locking shoulder 38 which is adapted to engage with the locking lug 33 of the controlling arm when the latter is elevated into its highest position and the key-lever is in its fully retracted position, as shown in Fig. 2. When the parts are in this position, the key lever holds the controlling arm against downward movement and the latter holds the gear segment against downward movement. If the gear segment while so held against downward movement is moved forward into engagement with the adjacent dial pinion, and the rocking frames are turned forwardly for depressing the gear segment, the spring 27 of this segment will be strained without, however, shifting the segment. At the end of this forward movement of the rocking segments, the roller 18 of the rock arm 13 drops off

100

105

110

115

120

125

130

from the rear end of the cam 14, the gear segment is moved rearwardly out of engagement from the dial pinion and then the rocking frames move backwardly without having shifted the dial. The upper arm of each key lever is provided on its front side with a vertical series of different stop shoulders 39, which are arranged step fashion and extend from the upper end of this arm downwardly and forwardly thereon or in other words the stop shoulders are arranged radially out of line with one another and different distances from the pivot of the key lever. These stop shoulders of the key lever are adapted to be moved forwardly into the path of the stop lug 34 on the controlling arm. The stop shoulders are arranged different distances from the stop lug 34 of the controlling arm, so that by moving different stop shoulders of the key lever into the path of the stop lug of the controller arm, the latter and the gear segment connected therewith may be arrested at different points in their downward movement. The uppermost stop shoulder of the key lever is most remote from the stop lug of the controlling arm and therefore requires the greatest forward movement of the key lever, in order to bring this stop shoulder into the path of this stop lug.

The stop shoulders of the key lever are so arranged that the distance from the stop shoulders to the path of the stop lug gradually grows less from the uppermost stop shoulder to the lowermost stop shoulder.

The relative position of the different stop shoulders of the key lever is such that when its locking shoulder 38 remains in engagement with the locking lug 33 and the gear segment is simply moved into and out of engagement with its dial pinion, the latter remains at zero, if the same has not been previously moved. But when the key lever has been moved forwardly, so as to disengage its locking shoulder from the locking lug and moves one of its stop shoulders into the path of the stop lug of the controlling arm, the latter arm and gear segment connected therewith will be moved downwardly upon moving the rocking frames forwardly, until the stop lug of the controlling arm strikes the respective stop shoulder of the key lever which stands in its path, as represented in Fig. 7, whereby the gear segment, while turning in engagement with the adjacent dial gear pinion turns the same forward. By turning the key lever forward more or less and moving one or the other of its stop shoulders into the path of the stop lug 34 of the controlling arm, the distance which this arm descends can be varied, thereby varying the number of spaces which its gear segment turns the adjacent dial.

Main number key mechanism.

40 represents the main keys whereby the

key levers of the main registering and recording mechanism are operated, and which are guided with their depending stems in the top 41 and bottom 42 of the key-board. As shown in the drawings, nine longitudinal columns of these keys are arranged transversely side by side. The first column on the right hand side of the machine contains seven keys and represents fractions of one-eighth of a cent, the next column toward the left contains nine keys and represents cents and the remaining columns of keys toward the left each contains nine keys and represents progressively higher orders of numbers according to the decimal system, so that the 75 registering keys in the last or left hand column represent hundreds of thousands of dollars.

The lowest numbers of the several columns of keys are arranged transversely in a row 85 on the rear part of the key-board and the corresponding higher numbers of the several columns are arranged likewise in transverse rows and progressively in their order toward the front end of the key-board.

Each of the registering keys is yieldingly held in an elevated position by a spring 43 surrounding the stem of the key and connected at its upper end to the key and bearing with its lower end against the bottom of the key-board. The upward movement of each key is limited by a shoulder 44 formed on the upper part of its stem and engaging with the underside of the top of the key-board.

The downward movement of all of the keys is substantially the same, but the arrangement of each column of keys lengthwise of the lower actuating arm of each key lever causes the keys to bear against their lever at different distances from its pivot so that by depressing different keys the same distance, the key lever will be turned different distances. The keys having the lowest numbers bear against their respective key levers nearest the pivot and consequently the levers are thereby thrown the greatest distance, and the uppermost stop shoulders are shifted into the path of the stop lug 34 of the respective controlling arms. The throw of each key lever upon depressing any one of its keys is so adjusted, that the proper stop shoulder on its upper arm is moved into the path of the stop lug 34 of the controlling arm and the downward movement of the respective gear segment is arrested after having turned the adjacent dial gear pinion a number of spaces corresponding to the number of the key which is depressed.

Loose connection for segments.

The loose connection between each controlling arm and its gear segment, heretofore referred to, is shown in its simplest form in the connection between the control-

125

130

ling arm and the gear segment, which are controlled by the initial or lowest column of registering keys. As shown in Figs. 1 and 22, the loose connection between the controlling arm and the gear segment of the lowest registering device consists of upper and lower guide lugs 45 and 46 arranged on the upper end of the segment and bearing against the upper and lower guide faces 47 and 48, which are formed on the upper end of its companion controlling arm. As the controlling arm and segment rise and fall, the guide lugs of the segment slide back and forth on the guide faces of the arm. The guide faces are so constructed that the back and forth movement of the segment on the arm is radially with reference to the dial pinion in all positions of the segment. By so forming the guide faces of the arm, the gear segment can be engaged with and disengaged from the dial pinion in all positions of the segment without disturbing the position of the dial pinion. The construction of the loose connections between the controlling arms and gear segments of all of the higher registering devices above the fractional registering device are combined with carrying devices, whereby each registering dial, upon making one complete turn, causes the next higher dial to be turned forward one space, thereby carrying up a number from one column to the next higher column. The loose connections between the controlling arms and the segments and the carrying mechanism of the higher registering devices are constructed as follows:

As shown in Figs. 1, 2, 7 and 22, each controlling arm is provided at its upper end with upper and lower guide faces 47 and 48 and its lower guide face is engaged by a lower guide lug 46 on the adjacent gear segment, the same as in the coupling between the controlling arm and segment of the initial registering device. The gear segments of the higher registering devices are each provided with an upper guide lug 49 which is adapted at times to bear against the upper guide face 47 of the companion controlling arm in substantially the same manner in which the upper guide lug 45 of the fractional gear segment bears against its companion arm the only difference being that the upper guide lugs 49 of the higher gear segments are held out of engagement and separated by a space from the upper guide face of the companion arm when no number is carried from a lower to a higher registering device. The upper guide lug 49 is held in this elevated position above the adjacent guide face by a rocking latch 50 which is arranged in a notch in the rear side of the gear segment and which normally projects toward the left and engages with the upper guide face 47 of the adja-

cent controlling arm, as shown in Figs. 2 and 16.

During the ordinary up and down movement of each higher controlling arm and gear segment, the latter is guided by its lower guide lug 46 and the locking latch 50 engaging with the lower and upper faces of the adjacent arm, this movement being the same as the movement of the controlling arm and gear segment of the fractional registering device. Normally the downward movement of the controlling arm is determined by the position of its companion key lever and this arm in turn controls the extent of the downward movement of the gear segment. When, however, the locking finger 50 is withdrawn out of engagement from the upper guide face 47 of the arm, the companion gear segment is capable of moving downward independent of the arm until the upper guide lug 49 engages with the upper guide face of the arm. The extent of this independent movement of the gear segment with reference to its companion arm is equal to one tooth or space of the segment, so that by this means the gear segment is enabled to turn the dial pinion one space more than the position of the key lever permits the same to move.

The withdrawal of the locking latch of each higher registering device is controlled by the next lower registering device and the withdrawal of each latch is effected when the next lower registering device has made one complete turn and arrived at zero. Each of the locking latches is pivoted on the right hand side of its adjacent gear segment, so as to turn transversely with reference to the latter. The latch is turned toward the left into its operative position by a spring 51, the movement in this direction being limited by a shoulder 52 arranged on the latch and bearing against the right hand side of the gear segment. 53 is an upright trip plate connected with the lower end of each latch and arranged normally at right angles or nearly so to the adjacent gear segment, when the latch is in its operating position. 54 represents a number of upright trip arms, each of which is controlled by a lower registering device and which turns the locking latch of the next higher registering device into an inoperative position. This arm is mounted loosely with its lower end on the supporting bar 35 and is provided at its upper end with a rearwardly and forwardly projecting hook 55, and in front and below said hook with a bend forming a bearing finger 56. 57 represents trip cams arranged on the left-hand side of each registering dial pinion and connected with the adjacent pinion and dial, but separated from the pinion by an intervening space or groove. The face of each of these cams may begin at its lowermost point near the axis thereof and then ex-

tend outwardly in a spiral line terminating with its highest point in line with its lowermost point with which it connects abruptly. The trip cam of the fractional registering device has its face divided into eight parts, each part of which except the first is arranged one-eighth of a space farther from the center of the cam than the preceding part, while the trip cams of the higher registering devices each has its face divided into ten parts, each part except the first being arranged one tenth of a space farther from the axis of the cam than the preceding part. Each of the trip arms 54 extends upwardly along the right-hand side of the trip cam of a lower registering device and its shoulder. 56 engages with the face of this cam, while the hook 55 at its upper end extends toward the left and is adapted to engage with the trip plate 53 of the next higher registering mechanism. In the initial position of each trip arm, its shoulder 56 engages with the lowest part of its trip cam. As the trip cam is turned in the direction of the arrow, Fig. 2, at the same time that its dial and gear pinion are moved forwardly by the adjacent gear segment during the adding operation, the trip arm is moved backwardly by the gradually rising face of the trip cam. During this backward movement of the trip arm, its hook engages with the trip plate 53 of the next higher registering device and is deflected toward the right thereby, the hook being sufficiently elastic for this purpose. After the hook has passed in rear of said trip plate, the hook owing to its resilience springs back to its normal position, so as to stand behind said trip plate. When the shoulder of the trip arm reaches the highest part of the face on the trip cam the trip arm has been shifted to its rearmost position. Upon now turning this cam forwardly another space together with its companion dial and pinion, the highest part of the cam is carried from underneath the shoulder of the trip arm and the latter is moved forwardly over the abrupt face of the cam until its shoulder 56 again engages with the lowest part of the cam face. During this movement of the trip arm, its hook strikes the rear side of the trip plate 53 of the next higher registering mechanism and turns the same forwardly, thereby disengaging the locking latch from the adjacent controlling arm and permitting the gear segment carrying the trip plate to move forward one space. The forward movement of the trip arm is effected when the dial with which its trip cam is connected has made one complete rotation and again stands at zero, whereby the addition represented by this complete rotation is carried to the next higher registering device. The forward movement of the trip arm is effected quickly by a spring 58, which connects with a stationary cross bar 59 ar-

ranged in front of the trip arms. The trip plate 53 of each registering device is so arranged and is of such length that the hook of the next lower trip arm can engage with the rear side of the plate, for disengaging its latch in any position of the gear segment carrying the plate and in order to accomplish this engagement it is obvious that cams 57 should be constructed so as to give arms 56 the proper throw. If a gear segment is locked in its highest position by reason of none of its companion keys having been depressed, the withdrawal of its latch from the controlling arm simply permits the gear segment to drop one space and turn its companion dial pinion forward one space, while in engagement therewith, the movement of this dial representing one number carried up from the next lower dial. If any one of the keys of the key levers has been depressed, so as to release the gear segment and permit the same to move downwardly for effecting an addition, and if during this time the next lower registering device has made a complete turn, so as to require the carrying up of a number from the next lower registering mechanism, the latch of the higher registering device will be withdrawn while the same is effecting its addition, thereby causing the segment to descend and turn its dial one space in addition to the space corresponding to the depression of its respective key.

When the locking latch has been withdrawn so as to permit a gear segment to move downwardly one space farther than its controlling arm, the latch remains in this position during the subsequent upward movement of the arm and the segment until the upward movement of the arm is arrested by striking the stop bar 32 and the gear segment continues its upward movement independent of the arm the extent of one space. The gear segment has now reached its highest position and its latch is again swung automatically by its spring over the controlling arm. The controlling arm and gear segment now remain in this relative position until another number is to be carried up from the next lower registering device. When the controlling arm has been retracted to its highest position the adjacent key lever is moved into its normal retracted position, so that its locking shoulder 38 engages with the locking lug 33 of the controlling arm and locks the latter against downward movement. The return movement of each key lever is preferably effected by a spring 60 which connects the upper arm of the key lever with the transverse shaft 9, as shown in Figs. 2 and 7, or with some other convenient part of the machine. The lower guide lug of the gear segment is not absolutely necessary because the weight of the parts connected with the controlling arm and arranged in rear of its pivot is sufficient to 130

raise the arm, but it is preferable to employ this lower guide lug 46 on the gear segment because it compels the arm to raise with the gear segment and avoids displacement of these parts with reference to each other, and also serves as a stop to limit the upward movement of the gear segment.

The gear pinion and the cooperating gear segment of the fractional registering device are so constructed that the fractional dial 10 makes one rotation whenever it is moved forward eight spaces. After the fractional dial has made one rotation the whole number represented by this rotation is transferred 15 by the first carrying device from the registering mechanism of the fractional dials to the next higher registering device which represents cents. The complete turns of each of the following registering devices 20 are in like manner carried or transferred to the next higher dial by the respective carrying device. The dial which records the highest number, in this instance the millions of dollars is preferably operated only 25 by the adjacent carrying device of the next lower dial and is incapable of being operated directly from the key-board because it is not provided with a key operating mechanism.

The mechanism whereby the dials are all 30 turned back to zero or the place of beginning after the addition of numbers has been completed is constructed as follows:

61 represents a series of feeling rock levers which are adapted to shift the key levers, so as to permit the gear segments to descend the proper distance for resetting or restoring the main registering dials to zero. One of these shifting levers is mounted loosely on the supporting bar 35 adjacent 40 to the left hand side of each of the key levers and is provided on its upper arm with a forwardly projecting feeling finger 62 and with a shifting finger 63 which extends behind the upper arm of the adjacent key lever, as 45 shown in Fig. 2. The feeling levers have their fingers arranged in rear of the total cams 57 and each of these levers is turned so that its upper arm moves backwardly by the upper arm of the adjacent key lever engaging 50 with the shifting finger 63 of the feeling lever. 64 represents a transverse pull-bar arranged in rear of the lower arms of the feeling levers and connected with each of the latter by a pull spring 65, as represented 55 in Figs. 2 and 7. This pull bar is connected at its ends to the lower ends of two depending pull or rock arms 66, which are secured at their upper ends to the rock shaft 9. Upon turning this rock-shaft, so as 60 to swing its depending pull arms backwardly the feeling levers are turned by means of the springs 65 so as to move the upper arms of these levers forwardly. This movement of the rock-shaft 9 is effected by a 65 cam 67, which is mounted on the left-hand

side of the rocking frame 29 and which is constructed substantially the same as the cam 14 which is mounted on the rocking frame 15. As shown in Figs. 15 and 19, this cam is pivoted at its rear end by a transverse pin to the rear portion of the rocking frame 29 and is provided at its front end with an incline or cam face 68, and in rear of the incline with a concentric face 69. The cam 67 is pivotally supported on the 75 rocking frame 29 in the same manner in which the like cam 14 is pivoted on its corresponding rocking frame 15.

The cam 67 can be raised and lowered with its front end into an operative or inoperative position, this movement being limited by means of a lug arranged on the cam and projecting into a slot in the adjacent rocking frame in the same manner in which the movement of the cam 14 is limited.

72, Figs. 15 and 17, represents a rearwardly projecting rock-arm secured to the rock shaft 9 and provided at its rear end with a roller or projection 73 which is adapted to be engaged by the cam 67 for turning 90 the rock shaft 9. When numbers are being added with the machine, the cam 14 is depressed, as shown in full lines, Fig. 2, so as to be in a position when moved forwardly by the rocking frame 15 to engage the roller 95 on the arm 72, for moving the gear segments into engagement with the dial pinions, and during this time the cam 67 is lifted into the position shown in full lines, Fig. 15, so that when the rocking frame 29 is moved 100 forwardly, the cam 67 will clear the roller 73 of the rock arm 72 and not disturb the rock-shaft 9 and the parts connected therewith.

If it is desired to restore all of the total 105 dials 2, to zero, the cam 14 is raised into its inoperative position, shown by dotted lines 14 in Fig. 2, and the cam 67 is lowered into its operative position, as shown by dotted lines 67a in Fig. 15. Upon now turning the 110 rock-shaft 20 by hand so as to move both rocking frames 15 and 29 forwardly, the cam 14 passes over the roller 18 of the arm 13 without disturbing the same, but the inclined front of the cam 67 engages with the 115 roller 73 on the rear end of the rock-arm 72 and raises the same until this roller engages with the concentric part 69 of this cam. By this movement of the arm 72, the rock shaft 9 is turned in the direction for moving 120 its depending arms 66 rearwardly and pulling the springs 65 rearwardly. This pull on the springs 65 causes the feeling levers to be turned until the feeling fingers of their upper arms engage with the spiral surfaces of 125 the trip cams. After the feeling fingers bear against these cams, their movement is arrested and the continued backward movement of the pull bar 64 simply stretches the springs 65 until the bar reaches the end of 130

its backward movement. The feeling finger of each feeling lever engages with that part of the surface of the adjacent trip cam which is directly opposite the feeling finger, 5 and as these trip cams are turned with the adjacent dial they present different parts of their spiral surfaces to the opposing feeling fingers, which causes the forward movement of the upper arms of the feeling levers to be arrested in different positions when 10 swung forwardly. During the forward movement of the upper arm of each feeling lever, its shifting finger 63 engages with the rear side of the upwardly projecting arm of the adjacent key lever and moves this arm forwardly. The construction of the parts is such that the spiral surfaces of the trip cam bears a definite relation to the step-shaped series of stop shoulders on the upper arm of 15 the key lever. When the feeling finger of the feeling lever, upon being moved forwardly, bears against the lowest key lever-stop-controlling part of the adjacent trip cam, the adjacent key lever is carried simultaneously forward with the feeling lever the greatest distance, and its uppermost stop shoulder is carried into the path of the stop lug of the controlling arm. The succeeding parts of the spiral surface of the trip cam 20 are so constructed that they rise progressively higher and arrest the forward movement of the feeling lever when the same has carried the adjacent key lever with its corresponding stop shoulder into the path of 25 the stop lug of the controlling arm. This forward movement of the feeling lever and that of the upper arm of the key lever is gradually reduced as the progressively higher parts of the trip cam are presented 30 to the feeling finger, and when the highest part of the trip cam is presented to the feeling finger, the feeling lever is prevented from moving forward at all and the upper arm of the key lever is not moved with its 35 locking shoulder out of engagement with the locking stop of the controlling arm and consequently the companion gear segment connected therewith is held against downward movement. After the rocking frames 40 to the feeling finger, and when the highest part of the trip cam is presented to the feeling finger, the feeling lever is prevented from moving forward at all and the upper arm of the key lever is not moved with its 45 locking shoulder out of engagement with the locking stop of the controlling arm and consequently the companion gear segment connected therewith is held against downward movement. After the rocking frames 50 and 29 have been turned forwardly sufficiently to engage the several feeling fingers of the feeling levers with their respective trip cams, the rear ends of the segmental notches 28 in the rocking frames engage 55 with the cross bar 25 and depress the same, thereby moving the lifting bar 22 downwardly and at the same time pulling down the springs 27. This downward pull on these springs causes each spring to pull its 60 respective gear segment down as far as possible, and after the downward movement of the segment has been arrested the continued downward movement of the cross bar 22 together with the rocking frames simply 65 stretches these springs until this bar reaches

the end of its downward movement. If a gear segment is locked in its uppermost or zero position its spring 27 will be stretched its full extent, whereas, if a gear segment moves downwardly more or less before it is arrested by its shifted key lever, its spring 27 will be stretched less in proportion. This downward movement of the gear segments which are free to move in this direction takes place while the gear segments are in their 70 retracted position and out of engagement from the dial pinions, so that the dials are not affected by this movement of the segments.

After the rocking frames have reached 80 the end of their forward movement and the roller 73 has dropped off from the rear end of the concentric portion 69 of the cam 67, the gear segments are moved forwardly by hand operated mechanism into engagement 85 with their respective dial pinions and are held in this position during the entire subsequent backward movement of the rocking frames, which is effected by hand operated mechanism. During the backward movement 90 of the rocking frames, the gear segments are raised to their highest positions, while in engagement with the dial pinions by the rod 22 and connecting parts and turn the dials backwardly. At the end of 95 the upward movement of the gear segments the latter are released, so as to permit them to move into their retracted position, out of engagement from the dial pinions.

During this operation, those gear segments which are held or locked in their highest positions, by reason of their dials being at zero, are simply moved forward at the end of the forward movement of the rocking frames, so as to engage with their 100 respective dial pinions and are again moved backwardly out of engagement therefrom at the end of the forward movement of the rocking frames, without disturbing their respective dials. Each of the unlocked gear 105 segments is moved downwardly a number of spaces corresponding to the number which is registered on its dial, the extent of this movement being controlled by the companion trip cam which arrests the forward 110 movement of the key lever, through the medium of its feeling lever, when the proper stop shoulder of the key lever has been presented to the controlling arm.

Upon now moving the gear segments forwardly in their variously depressed positions and then raising them to their highest position, each depressed gear segment will turn its dial backward the same number of spaces that the gear segment was depressed. Inasmuch as each gear segment was permitted to descend by its trip cam, feeling lever and key lever the same number of spaces as the number indicated on its dial, the gear segment subsequently moves upwardly the same 130

number of spaces before reaching its highest position, thereby turning its dial backwardly the same number of spaces and restoring the same to zero. When all of the dials have been returned to zero, the shoulders 56 of all the trip arms engage with the lowest parts of all of the trip cams 57.

The cams 14 and 67 are provided with a longitudinal slit 74, as shown in Fig. 13, so as to facilitate the manufacture of these parts. The mechanism whereby the positions of the cams 14 and 67 are reversed preparatory to restoring the dials to zero is constructed as follows:

The cams 14 and 67 drop into their operative position by gravity. Each of these cams is provided in rear of its pivot with a tail 75 which is depressed when it is desired to lift the respective cam into its inoperative position.

76 is a shifting lever which is pivoted at its lower end and is normally turned so that its upper end is disengaged from the rear side of the tail on the cam 14 by a spring 77, as shown in Figs. 2 and 7. The lever 76 projects in rear of the main frame so as to be accessible for manual operation. 78 is a shifting lever which is pivoted between its upper and lower arms and arranged with its upper arm in rear of the tail on the cam 67 and normally held in engagement therewith by a spring 79, as shown in Fig. 15. 80 represents an elbow lever pivoted below the bottom of the keyboard, as represented in Fig. 15. 81 represents a main line or cord which is connected with the lower arm of the elbow lever 80 and which is provided at its rear end with two branches 82 and 83. The branch 82 connects with the shifting lever 76 above its pivot, and the branch 83 connects with the shifting lever 78 below its pivot. 84 represents a total or shifting key having a depending stem which is guided in top and bottom of the key-board and which bears with its lower end against the upper arm of the elbow lever 80. Upon depressing the key 84, the elbow lever 80 is turned so as to draw the cords or lines 81, 82 and 83 forwardly, thereby moving the upper end of the shifting lever 76 into engagement with the tail of the cam 14 and lifting the same into an inoperative position, while the shifting lever 78 is moved rearwardly with its upper arm from the tail of the cam 67, thereby allowing the latter to drop into its operative position.

Upon depressing the gear segments while the parts are in this shifted position, the segments move downwardly out of engagement with the dial pinions. After the gear segments have been depressed they are moved forwardly into engagement with their respective dial pinions by an elbow lever 85 which is connected with its lower arm by a line or cord 86 to the rod or bar 7, as shown in Fig. 15, or to one of the rock

arms 8. The elbow lever is turned in the proper direction for this purpose by a shifting key 87 having a depending stem which is guided in the top and bottom of the key-board and which bears against the upper arm of the elbow lever 85. After the gear segments have been moved forwardly into engagement with the dial pinions, while in the depressed position, the gear segments are retained in forward position, and at the same time raised until they reach their uppermost position, whereby the dials are turned to zero. The shifting key 87 is now released which permits the spring 11 to move the gear segments rearwardly out of engagement with the dial pinions. The key 84 is also released, thereby permitting the shifting levers 76 and 78 to resume the positions shown in Figs. 2 and 15, leaving the machine in position to resume adding.

Each of the total dials is held against turning by means of a detent pawl 103 which engages with the front side of its companion gear pinion, as shown in Figs. 2, 7 and 9. The pawls 103 of the several gear pinions are mounted on a transverse pawl bar 104, which is supported at its ends by means of two pawl arms 105, which turn loosely upon the supporting rod or bar 35 of the key levers. The pawl arms are moved rearwardly for engaging the pawls of the bar 104 with the gear pinions by means of springs 106. These springs are connected loosely at their rear ends to the rock-shaft 9 and at their front ends to the pawl arms 105. During the forward movement of the gear segments preparatory to turning the dial pinions, the detent pawls are swung forwardly out of engagement with the dial pinions by means of two shifting rods 107 which are connected at their rear ends to opposite ends of the transverse rod 7 or some part moving therewith and each of which is provided at its front end with a fork or bifurcation 108, which engages with a pin or shoulder 109 on the pawl arm arranged on the adjacent side of the machine. As the gear segments move forward into engagement with the gear pinions the shifting rods 107 move the detent pawls 103 out of engagement with the dial pinions and when the gear segments move backwardly the detent pawls are again engaged with the dial pinions by the springs 106.

Recording mechanism.

For the purpose of recording the numbers which are added together by the above described mechanism a recording mechanism is provided which is constructed as follows:

140 represents a printing roller or platen which is arranged transversely in the upper, rear part of the machine and under the lower side of which the sheet or other ar-

tile is placed which receives the record. 141 represents a number of type segments which are arranged transversely side by side below the platen and which are pivoted at their front ends to the supporting bar 31 upon which the rear ends of the controlling arms 30 are pivoted. Each of these type segments is provided at its rear end with a segmental row of type carriers 142, which are capable of moving radially back and forth on the type segment. Each of the type carriers is provided at its rear end with a type and is guided upon the type segment by means of screws or rivets 143 secured to the type carrier and arranged in radial slots 144 formed in the type segment, as shown in Figs. 2, 3 and 11. Each of the type carriers is held in its inward or retracted position by means of an S-shaped spring 145, which is arranged between the carrier and the type segment and is secured with one end to the carrier and with its other end to the type segment. Upon raising or lowering the type segment any one of its type can be brought to the printing point or line, and upon striking the back or inner end of the type carrier, when the same is in line with the printing point the type carrier will be driven outwardly and its type will produce an impression on the sheet supported by the platen. After the carrier has received the blow for driving the same against the platen, the carrier is again quickly retracted to its innermost position by means of its spring.

Each of the type segments is connected with one of the controlling arms, so that upon depressing a controlling arm and the registering gear segment connected therewith, the companion type segment will be raised and present one of its type to the printing point.

For convenience in operating the machine, the keys are separated a considerable distance on the key-board and in order to produce a compact record, the printing segments are arranged closer together than the keys and the registering mechanism. In order to permit of this arrangement, each type segment and its corresponding controlling arm are connected by a connecting arm 146, as represented in Figs. 1, 2 and 16, the connecting arms of the central controlling arms and type segments are comparatively straight, but the connecting arms of the outer type segments and controlling arms are arranged obliquely, the degree of this obliquity gradually increasing from the central type segments and controlling arms in opposite directions toward the outer type segments and controlling arms, as represented in Fig. 1. The connecting arms 146 of the outer controlling arms are arranged

in the spaces behind the upright parts and above the horizontal parts of the controlling arms, thereby permitting the inner controlling arms to move up and down without interfering with the connecting arms 146 of the outer controlling arms.

The types on each type segment are arranged to correspond with the teeth and numbers of its companion gear segment and registering dial, the zero type being at the upper end of the series and the progressively higher digits arranged in their order downwardly from the zero type. When the registering gear segment is in its highest position it presents its zero tooth to the dial pinion, and the type segment which at this time is in its lowest position presents its zero type to the printing point. Upon depressing a gear segment so as to preset one of its higher teeth to the dial pinion, its companion type segment is raised proportionally and presents a corresponding higher numbered type to the printing point.

147 represents a number of hammers whereby the type carriers are struck for driving the type against the platen. One of these hammers is arranged adjacent to each type segment and is provided with a head which is arranged in front of the series of types and in line with the printing point of the platen. Upon shifting the type segment so as to bring one or another of its type carriers to the printing line and then operating the hammer, the latter delivers a blow against the inner end of the particular carrier which is at the printing point and produces an impression of its type on the platen. The several hammers are pivoted on the transverse rod 12, arranged in rear of the segments; and each of the hammers is yieldingly held in its forward position by a spring 148 connected at its lower end to a cross bar 149 and at its upper end to a depending arm 150 on the hammer.

151 represents a vertically movable trip bar or rod which is arranged transversely below the hammers and whereby the latter are operated. This bar is supported at its ends upon the rear ends of rock arms 152 which turn loosely with their front ends on the rod 31 supporting the type segments and controlling arms.

153 represents a number of hammer or trip pawls, whereby the hammers are retracted preparatory to delivering a blow against the type carriers which are at the printing point. One of these pawls is arranged adjacent to each hammer and pivoted loosely at its lower end to the trip bar 151, and its upper end is provided on its rear side with a downwardly facing hook or shoulder 154, and above said shoulder with a trip face 155, as shown in Figs. 3 and 6. Each of the hammers is provided in front of its pivot adjacent to the upper

end of the hammer pawl with a lower trip lug or shoulder 156 and an upper trip lug or shoulder 157. When the parts are at rest, the hammer pawl 153 is raised into its highest position and the hammer is in its normal position with its lower trip lug 156 below and in rear of the hook of the hammer pawl and with its upper shoulder 157 in rear of the trip face of the hammer pawl, as represented in Figs. 2 and 3.

Upon shifting the hammer pawl rearwardly, while the parts are in this position, so that its hook overhangs the lower shoulder 156 of the hammer, and then pulling the hammer pawl downwardly, the hook of the hammer pawl engages with the lower shoulder of the hammer and turns the same so that its head is retracted from the type carrier at the printing line. As the hammer moves downwardly with the hammer pawl, the upper shoulder of the hammer comes into engagement with the trip face of the hammer pawl and during the continued downward movement of the hammer and its pawl, this upper shoulder gradually crowds the hammer pawl forwardly with reference to the hammer by reason of the hammer and its pawl swinging on different centers. During the last portion of the downward movement of the trip bar 151 and the hammer pawl mounted thereon, the pawl is crowded forwardly by the upper shoulder 157 of the hammer to such an extent that its hook is disengaged from the lower shoulder 156 of the hammer, thereby liberating the latter and permitting its spring 148 to throw the same quickly and deliver a blow against the type carrier at the printing line. The trip bar 151 now rises and carries the hammer pawl into its highest position, preparatory to again engaging the hammer for depressing the same.

158 represents a number of upright shifting arms whereby the hammer pawls are moved rearwardly, so that their hooks engage with the lower shoulders of the hammers. One of these arms is arranged adjacent to each hammer pawl, as shown in Figs. 3 and 6 and is pivoted at its lower end on the trip bar 151, and its upper end is provided with a roller or projection 159 which bears against a hammer cam 160 on the lower part of the adjacent type segment, as shown in Figs. 3, 7 and 16. This hammer cam is provided at its upper end with a receding or low portion, an inclined portion arranged below the low portion, and a concentric or high portion arranged below the inclined portion. Each shifting arm 158 is moved forwardly and its roller is yieldingly held in engagement with the adjacent hammer cam by a spring 161 connecting said arm with a cross bar 162 secured to the rock arms 152, as represented in Figs. 7 and 8. The backward movement

of each hammer pawl with reference to its companion shifting arm, is limited by means of a stop 163 secured to the upper portion of the hammer pawl and engaging with the front side of the shifting arm, as represented in Figs. 3, 5 and 14.

Each hammer pawl is yieldingly held in its rearmost position with reference to its shifting arm by means of a C-shaped spring 164 secured with its ends, respectively, to the hammer pawl and its shifting arm, as shown in Figs. 2, 3 and 14. In the lowermost position of a type segment the receding part of its cam is presented to the roller of the shifting arm 158, which permits the hammer pawl to be retracted into its foremost position, as represented in Fig. 2. Upon depressing the trip bar 151 when the parts are in this position, the roller 159 is not engaged soon enough by the incline of the cam 160 to engage the hook of the hammer pawl with the lower shoulder of the hammer, before the hook has passed below this shoulder; but instead the trip face of the hammer pawl slides idly against the shoulder 156 without retracting the hammer, whereby no impression of the particular type at the printing line is produced. If the type segment is raised, so as to present one of its lower types to the printing point 95 or line, the incline of its cam, during the first part of the upward movement of the segment moves the shifting arm 158 rearwardly together with the hammer pawl, yieldingly connected therewith, so that the hook of the hammer pawl stands over the lower shoulder 156 of the hammer. Upon now depressing the pawl 153 the hammer will be retracted and released near the end of the downward movement of the pawl 105 and will be quickly swung up by the spring 148, thereby delivering a blow against the type at the printing point and producing an impression thereof.

The incline 160 of the type segment cam is so constructed that it throws the hammer pawl backwardly into an operative position when the segment is raised one digit space, and during the continued upward movement of the segment, the hammer pawl is held in this operative position by the high concentric part of the segment cam. By thus constructing the type segment cam, its companion hammer pawl is not shifted when the segment is not raised and its zero type 115 remains at the printing line, but the hammer pawl is shifted into an operative position for producing an impression, if the type segment is raised one or more digit 120 spaces and presents any one of its digits 125 higher than zero to the printing line.

Automatic printing of zero.

165 represents a number of transfer or coupling fingers which enable the ciphers 130

in a number to be printed automatically. One of these transfer fingers is secured to each of the shifting arms 158, as represented in Figs. 3, 7 and 14, and extends laterally 5 toward the right therefrom into engagement with the shifting arm of the next lower hammer pawl, as represented in Fig. 19. If any one of the printing segments remains in its lowest position, so that its 10 cipher remains at the printing line and the next higher printing segment has been raised for printing a higher number or digit, the transfer finger of the higher hammer shifting arm 158 while being moved 15 rearwardly by the cam of its companion printing segment, is caused to engage with the shifting arm 158 of the next lower hammer pawl and shift the latter backwardly, so that its hook is carried backwardly over 20 the lower shoulder of the companion hammer. Upon now depressing the trip bar 151, the higher hammer pawl 153 is coupled with its hammer and the next lower hammer pawl is also coupled with its hammer, 25 whereby an impression of the cipher or zero type on the lower segment is produced on the platen at the same time that the next higher number is printed on the platen.

If two ciphers occur in succession in 30 the body of a number, the shifting arm to the left of the highest order printing segment to be operated for printing a zero sets the hammer mechanism of said highest zero-printing segment by means of the transfer 35 finger of said shifting arm and the shifting arm of said highest zero-printing segment in turn by means of its transfer finger sets the hammer mechanism of the printing segment of next lower order, etc. This operation of producing an impression of the 40 cipher type is effected automatically and renders it possible to print any number of ciphers in succession in the body of a number because the hammer operating mechanism of each segment which remains standing with its upper type at the printing line is controlled by the hammer operating mechanism of a higher type segment and in turn controls the hammer operating mechanism of the next lower type segment, if the 45 next lower segment presents a cipher to the printing line.

Only the ciphers below the highest digit in the number to be recorded are thus 50 printed automatically because the printing of a digit depends upon the upward movement of a printing segment, thereby avoiding the printing of ciphers ahead of the highest digit in the number to be recorded. 55 The hammer shifting device of the segment which prints the numbers representing units of cents is preferably, not provided with a transfer finger to operate on the hammer shifting device of the segment which prints 60 fractions of a cent, because it is proper that

the space to the right of the lowest integer shall remain blank when no fraction is recorded therein.

The carrying bar 151 is raised by one or more springs 166 which connect this bar with 70 the transverse rod 12, as shown in Fig. 8, and the upward movement of the bar 161 is arrested when the hammer operating pawls reach their highest position by a transverse bar 167 which is engaged by the rear ends of 75 the rock arms 152. 168 represents a coupling hook, whereby the hammer trip devices are depressed. This hook is pivoted with its upper end to the trip bar 151 and its lower engaging end is provided with a 80 notch having upper and lower shoulders.

In the lowered position of this hook its notch engages with a cross bar 169 which is connected with the rock arms 24, as represented in Figs. 2 and 7, so that the hook and 85 the hammer operating devices connecting therewith are actuated from the rocking frames 15 and 29, through the medium of the rock arms 24. In the rearmost position of the rocking frames, the front ends of 90 their notches 28 bear against the front side of the bar 25 to which the gear segments are yieldingly connected and the cross bar 169 bears against the rear or upper shoulder of the notch of the hook 168, as represented 95 in Fig. 2.

Upon swinging the rocking frames forward, the incline of the cam 14 first raises the rock arm 13 and shifts the gear segments into engagement with the dial pinions, and 100 after the segments have been so shifted, the rear shoulders of the notches 28 in the rocking frames engage with the cross bar 25, so that thereafter this bar is carried downwardly with the rocking frames and the 105 gear segments are depressed. During this downward movement of the bar 25 with the rocking frames, the companion bar 169 moves down idly in the notch of the hook 168 until this bar engages with the lower or 110 front shoulder of this hook. After the cross bar 169 engages with the lower shoulder of the notch of the hook, the latter and the hammer operating devices connected therewith are moved downwardly with the rocking frames until these frames reach the end 115 of their downward movement. During the last portion of the downward movement of the rocking frames the hammer pawls are disengaged, as before described, from the 120 retracted hammers, whereby the latter are released and strike the type carriers which are at the printing line. By this means, the blow of the hammers is delivered after the registering of the numbers has been effected 125 on the dials and the type segments have been shifted into their proper position for recording the respective number.

The hammers do not follow the type carriers to the end of their outward movement 130

but are stopped short, after delivering a blow against the inner ends of the carriers by their depending arms 150 engaging with a rubber facing 170 on the cross bar 167, as shown in Fig. 3, so that the types are moved outwardly by the impact of the hammers and are then returned by their springs so as to clear the printing surface.

When it is desired to print or record the total at the foot of the column of the numbers which have been printed, the operation is as follows: The total key 84 is first depressed, thereby raising the cam 14 into an inoperative position and lowering the cam 67 into an operative position. Upon now moving the rocking frames 15 and 29 forwardly the feeling levers 61 are turned so as to move their feeling fingers forwardly into engagement with the respective cams 57 and 20 at the same time each feeling lever carries the adjacent key lever forwardly so that its particular stop shoulder 39 corresponding to the position of the trip cam 57 and its dial is moved into the path of the stop lug 34 of the controlling arm. After the key levers have been thus shifted forwardly into their respective positions corresponding with their dials, the continued forward movement of the rocking frames causes the gear segments 30 while in a retracted position out of engagement with the dial pinions to be depressed until each segment is arranged by the engagement of the stop lug on its controlling arm with its respective stop shoulder of its key lever, whereby each printing segment is raised so as to present the type carrier to the printing point which carries the type corresponding to the number registered on its companion dial. During the last part of the forward and downward rocking movement of the rocking frames the hammers are operated and the particular type at the printing line are impressed on the platen. Upon now springing the rocking frames backwardly, the gear segments are raised while still in a retracted position, out of engagement with their companion dial pinions, thereby permitting further numbers to be added to the total already registered on the 45 dials. If, however, it is desired to turn the dials back to zero, after the total of the added numbers has been printed or recorded the gear segments, while in the retracted lower position which they occupy while 50 printing the totals, are moved forwardly into engagement with their respective dial pinions by the depression of the key 87. Upon now moving the rocking frames backwardly the gear segments are raised while in 55 their forward position in engagement with their pinions, whereby each of the latter is turned backwardly and when the segments reach the end of their upward movement, the dials have been turned backwardly a 60 number of spaces corresponding to the num- 65

ber on the dial, thereby turning all of the dials to zero.

In the highest registering and recording mechanism which registers and records the highest numbers for which the machine is designed, the stop arm 37 having the differential stops, is not provided with a lower key operated arm 36, because the arm 37 is only used to arrest its gear segment and printing segment at different points, for setting the parts preparatory to turning the highest dial to zero or for printing the total of the number indicated by the highest total dial.

Duplicate printing by counterpart types. 80

For the purpose of permitting the numbers to be printed in duplicate, for instance, when it is desired to print an amount on a bank check, and the same amount on a stub, the machine is provided with mechanism which is constructed as follows:

1410 represents a number of duplicate printing or type segments which are arranged transversely in line and preferably toward the right of the main printing segments 141, as represented in Figs. 1, 17, and 19, and which are pivoted loosely at their front ends on the supporting rod 31. One of these duplicate number printing segments is provided for each of the main number printing segments and each duplicate segment is connected with its companion main segment by a U-shaped frame which is connected by the upper ends of its arms 189 to its duplicate and main segment and has its cross bar 190 arranged transversely below the intervening segments, as shown in Figs. 1, 2, 4, 7 and 21. The cross bars 190 are arranged sufficient distances below the segments so that each pair of connected main and duplicate printing segments can be raised to its highest position without interfering with the other segments. For the purpose of permitting the connecting frames 110 of the several pairs of printing segments to be arranged compactly, the arms of the connecting frame are curved concentrically with the pivots of the segments, as represented in Figs. 2 and 4. 115

Each of these duplicate printing segments is provided with type carriers corresponding to and constructed the same as the type carriers of its companion main segment and each of these duplicate segments is provided 120 with a hammer operating device which is constructed the same as the hammer operating devices of the main segments, and the same description and reference characters, therefore apply to the details of both the 125 main and duplicate printing segments.

Horizontal ruling.

For the purpose of producing horizontal or cross ruling upon the sheet or surface 130

which receives the record, the following mechanism is provided:—

193 represents the lowermost type carrier of each of the number printing segments, each of which is provided at its rear end with a horizontal ruling type. Each of these ruling type carriers is constructed the same as the number type carriers with the exception that the front end of each 10 ruling type carrier is widened horizontally, preferably, in both directions in the form of the letter T, as shown in Fig. 20, and the ruling type extends transversely from end to end of the widened part of this carrier, 15 so that the ruling types, when placed transversely in line and driven against the platen, will produce a practically continuous line transversely on the recording surface. Each of the number key levers is provided 20 on the front side of its upper arm with a ruling stop or shoulder 194, which is arranged one space below the lowermost number registering stop or shoulder 39.

Upon swinging the key levers, so as to 25 bring their ruling shoulders 194 into the path of the lugs 34 of the controlling arms, the latter together with the gear segments connected therewith are depressed upon moving the rocking frames 15 and 29 forwardly until the stop lugs 34 of the controlling arms engage with the lowermost or ruling shoulders 194 of the key levers. When 30 the controlling arms reach this lowermost position, the printing segments connected therewith have been raised to their highest 35 position and present the ruling types of all of the segments to the printing line. During the last portion of the forward movement of the rocking frames 15 and 29, while 40 the ruling types are at the printing line, the proper hammers are operated for producing an impression of these types.

The key levers are turned simultaneously 45 for bringing all of their ruling shoulders simultaneously into the path of the stop lugs of the respective controlling arms by means of a rocking plate 195 which is arranged transversely in front of the lower arms of the key levers and overhangs the front ends 50 thereof as represented in Figs. 2 and 7. This rocking plate is secured to a transverse rock shaft 196 which is journaled in the frame of the machine and which is turned for holding the rocking plate in its 55 uppermost position out of engagement from the key levers by means of a spring 197.

198 represents a shifting key whereby the 60 parts are shifted to permit of producing cross or horizontal ruling. This key is provided with a depending stem which is guided in the top and bottom of the keyboard and which engages against the rear end of a rock arm 199 projecting rearwardly 65 from the rock shaft 196, as represented in

Fig. 15. Upon depressing this key, the rocking plate 195 is turned in the direction for depressing the front arms of all the number key levers and bringing the ruling shoulders 194 on the upper arms thereof 70 into position for arresting the type segments during their upward movement when the ruling types arrive at the printing point.

In order to prevent the gear segments from meshing with the dial pinions during 75 the cross ruling operation the position of the cams 14 and 67 is reversed at the same time that the plate 195 is depressed. This is effected by a depending arm 1960 secured to the shaft 196 and connected by a cord 80 or wire 1961 with the branch wires 82, 83 leading to the shifting levers 76 and 78, as represented in Fig. 15. When it is desired to produce horizontal ruling on the recording surface, the key 198 is depressed thereby 85 raising the cam 14 into an inoperative position, depressing the cam 67 into an operative position and moving all the number key levers with their ruling shoulders 194 into the paths of the stop lugs of the controlling 90 arms. Upon now moving the handle 21 forwardly, the rocking of the frames 15 and 29 first causes the gear segments together with their controlling arms to be moved downwardly until arrested by the ruling shoulders of the keys, in which position of the parts, the printing segments have been raised with their ruling types to the printing line. The continued forward movement 95 of the rocking frames operates the hammer 100 tripping mechanism and produces an impression of the ruling types on the recording surface. Upon now moving the handle 21 backwardly and releasing the key 198, the parts resume their normal position. 105 While the cams 14 and 67 are reversed so as to move the gear segments downwardly out of engagement with the dial pinions for producing horizontal ruling, the feeling levers are also shifted, but this movement of the 110 feeling levers is of no effect.

Word printing mechanism.

For the purpose of permitting words to be printed in front of the numbers which are 115 added together the following mechanism is provided:—

1411 represents a word printing segment which is mounted loosely on the rod 31 next to the highest number printing segment of 120 the main number recording mechanism, as represented in Figs. 1, 2, 17, and 19. This segment is provided with a number of radially movable carriers 1420, which are constructed the same as the carriers of the number printing segments and each of which is provided on its face with a word type. The words of these types are selected according to the purpose or business for which the machine is to be used. For instance, if the 130

machine is to be used in a bank, types representing the words "vouchers," "checks," "drafts" "bills," and similar words common to the banking business may be used. When 5 the machine is designed for use in a restaurant, the words "soup," "vegetables," "meats," "dessert," and other words peculiar to this business may be used.

The position of the word-type segment is 10 controlled by a key lever 3600, Fig. 8, which turns on the bar 35 is similar to the number key levers, and is provided on the front side of its upper arm 3700 with a vertical series of differential stops or shoulders 3900 which 15 are adapted to be engaged by the stop lug 3400 of a controlling arm 3000; and lever 3600 is also provided with a locking stop or shoulder which is adapted to be engaged by a locking lug 3300 on the controlling arm, as 20 represented in Fig. 8. The controlling arm 3000 is connected with the word-printing segment by a connecting bar 1460. The stop shoulders on the upper arm of the word-key lever are so arranged that upon 25 swinging this lever so as to carry different shoulders into the path of the stop lug on the controlling arm, the latter will be arrested at different points in its downward or forward movement and the word-printing 30 segment connected therewith will be stopped at different points in its upward movement and present the particular word type to the printing point which corresponds with the shoulder or stop on the word-key lever.

35 The upward movement of the controlling arm 3000 is limited by its rear locking lug 3800 engaging with the stop bar 32 which arrests the upward movement of the controlling arms 30 of the number registering 40 and recording mechanism. The downward movement of the controlling arm 3000 and the simultaneous upward movement of the word printing segment is effected by a spring 215 which yieldingly connects this arm with 45 the bar 25 to which the registering gear segments are connected.

216, Fig. 1, represents a row of word-keys having depending stems which are guided in the top and bottom of the key-board and 50 which engage against the upper side of the front arm 3600 of the word key lever at different distances from the fulcrum thereof. Upon depressing any of the word-keys, the word-key lever will be turned the proper 55 distance to bring its proper stop shoulder into the path of the stop lug of the companion controlling arm and arrest the word-type segment during its upward movement, when the word-type corresponding with the 60 word of the depressed key has reached the printing line. When the respective word-type is in this position the same is driven against the recording surface for producing an impression thereon, at the same time that

the printing of the numbers by the number-printing segments is effected. The word-types are driven against the platen by a hammer operating mechanism which is constructed the same as the hammer-operating devices of the number printing mechanism and the same reference characters are therefore used to denote the same. The word-key lever is yieldingly held in its normal position by a spring 600.

75

Auxiliary adding mechanism.

An auxiliary adding mechanism is provided which permits of effecting an addition of numbers different from the numbers which are added by the main adding mechanism.

This auxiliary adding mechanism is constructed as follows:

2000 represents a number of auxiliary dials which are mounted on the left hand end of the dial shaft 3. 5000 represents a number of auxiliary gear segments which are mounted on the transverse rod 7 and are adapted to engage with gear pinions 400 on the auxiliary dials, as represented in Fig. 9. 90 Each gear segment 5000 is connected with a controlling arm 3001 arranged adjacent to the gear segment by a latch or coupling which at times permits the segment to move independently of the controlling arm. 3601 95 and 3701 represent auxiliary key levers which are operated by auxiliary keys 401 and which control the operation of the auxiliary registering and recording mechanism. The detail construction of the dials, gear 100 segments, printing segments, key levers and the parts co-operating therewith of the auxiliary registering and recording mechanism is substantially the same as the construction of the same parts in the main registering and recording mechanism except as hereinafter 105 distinguished and the same reference characters are therefore employed to denote like parts in both of these sets of mechanism.

In the drawings, two auxiliary key levers 110 and three auxiliary dials are shown which permits of registering and recording a total of 999, but additional registering and recording devices may be employed if it is desired to increase the capacity of the machine.

In the auxiliary mechanism each of the higher gear segments 5000 is provided with a pivot latch 501 the same as in the main registering mechanism. The lowest or 120 primary gear segment of the auxiliary registering mechanism is shown provided with a movable latch 502, which is utilized in the parent application for the purpose of effecting counting, but for the purpose of the 125 present application this segment might be the same construction as the primary gear segment of the main registering mechanism.

5 In the auxiliary registering mechanism the gear segments are not provided with lower stops 46 like those of the gear segments of the main registering mechanism 5 which permits the auxiliary controlling arms to move downwardly when necessary independently of the auxiliary gear segments. The upward movement of the auxiliary gear segments is limited by stops 10 218 with which the upper ends of the gear segments engage. 219 represents a foot formed on the lower side of each controlling arm 3001 and adapted to engage with the lifting cross bar 22. The auxiliary registering and recording mechanism could for the purposes of the present application be made in all ways similar to the main registering and recording mechanism, as the variations mentioned are for the purposes of counting 15 and numbering which are not shown nor described nor claimed in the present application. For the purpose of effecting an ordinary addition of numbers on the auxiliary registering mechanism, the auxiliary key levers are shifted into the proper position by the depression of the keys 401 representing the numbers to be added and then the rocking segments 15 and 29 are turned forwardly. 20 During the forward movement of the rocking frames the auxiliary gear segments are first moved into engagement with the auxiliary dial pinions by the cam 14 and then pulled down by the springs 27, and the controlling arms are also pulled down by the latches of the gear segments engaging with the controlling arms. The downward movement of the gear segments and controlling arms continues until the stops 34 of the controlling arm strike the shoulders 39 on the key levers which stand in the path of the stops 34. At the end of the forward movement of the rocking frames the gear segments are withdrawn from the dial pinions 25 by the springs 60 and during the subsequent backward movement of the rocking frames the gear segments and controlling arms are raised by the cross bar 22 engaging with the gear segments and with the feet 219 of the arms. The carrying of numbers from the units dial to the tens dial and from the latter to the hundreds dial and the turning of the dial to zero is effected in the same manner as in the main registering mechanism. 30 By this organization of the machine, numbers such as sales or pieces of goods can be added and recorded by the main registering mechanism and other numbers such as the rebate on sales and discount on the prices of 35 the goods, can be separately added or recorded by the auxiliary registering mechanism.

The key controlled devices whereby the parts of the main registering and recording

mechanism are shifted into the proper position preparatory to registering and recording a number are distinct from the key controlled devices whereby the same effect is produced in the auxiliary registering and recording mechanism, but both sets of registering and recording mechanisms are operated simultaneously by the one universal shifting mechanism for effecting the registration and recording of the numbers which are represented by the different positions of both key controlled devices. 65 70 75 For the purpose of permitting counting of the separate number of additions which has been effected on the main registering mechanism the auxiliary adding mechanism is constructed as follows: 80 85 90 95 100 105 110 115 120 125 220 represents springs whereby the auxiliary controlling arms are connected with the cross bar 25. The springs 220 of auxiliary controlling arms are provided at their lower end with vertically elongated loops 221 which receive the bar 25, as shown in Fig. 9, and which form a slack connection between the springs 220 and the bar 25. 102 107 112 117 122 127 132 137 142 147 152 157 162 167 172 177 182 187 192 197 202 207 212 217 222 227 232 237 242 247 252 257 262 267 272 277 282 287 292 297 reference is hereby made. For the purpose of the present application any suitable means may be employed for the purpose of holding the platen in printing relation with the printing types.

The record sheet is fed forwardly underneath the platen and upwardly in front of the same, so that the sheet passes the printing line. The sheet is pressed against the underside of the platen, in rear of the printing line, by a transverse presser roller 270 arranged below the platen and journaled with its ends in the front arms 261 of the paper carriage.

15 *Platen feed or line-spacing.*

283 represents a platen feed lever which is pivoted loosely on the left end of the platen shaft and which is provided on its rearwardly projecting arm with a pawl 284 which engages with a ratchet wheel 285 secured to the adjacent end of the platen, as represented in Figs. 1 and 15. 286 represents an intermediate actuating lever which is pivoted on the lower part of the front carriage-arm 261 which is adjacent to the ratchet wheel 285. The ratchet lever is connected with the intermediate lever by means of a link 287 which is pivoted at its upper end to the rear arm of the ratchet lever and is provided at its lower end with a loop 288 which receives the rear arm of the intermediate lever. 289 represents a spring which connects the front arms of the ratchet lever and intermediate lever. The upper end of this spring is connected with the front arm of the ratchet lever a greater distance from the pivot of the latter than the distance between the connection of this spring with the intermediate lever and the pivot of the latter. By this connection of the spring 289, the leverage of the ratchet lever is greater than that of the intermediate lever, which causes this spring, when both of these levers are free, to turn these levers simultaneously in the direction for raising their rear arms, thereby moving the ratchet pawl upwardly or backwardly for taking up a new tooth on the ratchet wheel.

59 The ratchet pawl is yieldingly held in engagement with the ratchet teeth by means of a spring 290. The movement of the intermediate lever in the direction for raising its rear arm and moving the ratchet pawl backwardly is limited by means of a nose 291 formed on this lever and engaging with a stop on the adjacent arm of the carriage as represented in Fig. 15.

The rocking motion of the intermediate lever is always the same, and in order to enable the same to turn the platen different distances, the rear arm of the intermediate lever is provided on its under side with a number of notches 292 which are arranged

different distances from its fulcrum, and one or another of which is engaged by the lower end of the loop 288 on the connecting link 287. Upon engaging this loop with the notch of the intermediate lever nearest its axis, the ratchet pawl is shifted so that the platen is turned one line-space at a time; while upon shifting this loop into engagement with one of the outer notches of the intermediate lever, the platen will be turned forward by its ratchet mechanism a correspondingly greater distance by the operation of the machine.

The intermediate lever is turned in the direction for shifting the platen by a transverse bar 293 arranged below the front arm thereof, as represented in Figs. 1, 2, 7, 15 and 19. This bar is supported upon the upper ends of two rock arms 294 which are mounted loosely with their lower ends on the cross bar 167. 295 represents a depending arm which is preferably formed in one piece with that one of the arms 294 arranged on the left hand side of the machine. This depending arm is provided with a nose which is arranged to rear of and in the path of the rocking frame 29.

During the last position of the rearward movement of this rocking frame, it engages with the nose of the depending arm 295 and moves the same rearwardly, and the upper arms 294 connected therewith are moved forwardly, thereby causing the cross bar 293 to be carried upwardly and turn the intermediate lever in the direction for feeding the platen and paper forwardly. During the forward movement of the rocking frame 29, the rock arms 294 are turned backwardly together with the intermediate lever and connecting parts by the spring 289 preparatory to feeding the platen forward the next space. As the line-spacing of the record sheet by feeding the platen occurs after each item is printed and in the same operation in which said item is printed, the printed record is fed up into visible position at each operation of the machine.

If desired, the platen may be turned by hand when it is desired to adjust the paper, this being effected by releasing the pawl 284 from the ratchet wheel and then turning the platen by means of a button 296 secured to end of the shaft, as shown in Figs. 1, 17 and 19.

The cross bar 293 extends a sufficient distance transversely of the machine so as to engage with the front arm of the intermediate rock lever 286 in all the positions which the paper carriage can be shifted transversely in the machine.

125 *Horizontally movable carriage.*

The paper carriage is capable of sliding lengthwise on the rods 263 and 265 for pre-

senting different parts of the paper to any particular type and is held in its adjusted position by a spacing device which consists of a graduated adjusting sleeve 301 and an 5 adjusting catch 302, as represented in Figs. 2 and 18. The adjusting sleeve is revolubly mounted on the supporting sleeve 260 between the carriage frame arms 261 and is provided with two or more longitudinal 10 series of stop notches or graduations 303, 304. The notches in each series may be equidistant and the notches in one series are spaced different from the notches in the other series, as shown in Fig. 18. The catch 15 302 is pivoted on the rod 167 and is yieldingly held in engagement with any one of the notches in the adjusting sleeve 301 by a spring 305. When it is desired to shift the carriage intermittently short distances 20 lengthwise of the platen for writing narrow columns, the adjusting sleeve is turned so as to present its closely spaced notches to the catch and the latter is shifted from one of these notches to another as the writing 25 progresses. When wider columns are to be written the adjusting sleeve is turned so as to present correspondingly wider spaced notches to the catch. As shown in the drawings, only two series of adjusting notches 30 are provided on the adjusting sleeve, but more series of notches may be provided if necessary.

Any suitable inking means may be employed, and the mechanism shown for this 35 purpose is not fully described in this application, as this specific structure is not an essential part of the invention claimed herein. This specific inking mechanism is fully described in the parent application Serial 40 No. 1,004 and is fully described and claimed in another divisional application Serial No. 254,065 to which reference is hereby made.

Any suitable full stroke mechanism may be pivoted to prevent the operator from 45 making only a partial forward and backward stroke of the rocking frames 15 and 29, and the mechanism shown for this purpose is not fully described in this application. This specific structure is not an essential 50 part of the invention claimed herein, and is fully described and claimed in various combinations in the parent application Serial No. 1,004, and in the divisional applications Serial Nos. 183,397 and 183,398, 55 to which reference is hereby made.

Any suitable mechanism may be provided 60 to hold the keys when they are moved from normal to operative position, and to release the number keys upon operating the operating mechanism and upon operating the total 65 key, and the mechanism for this purpose is not fully described in this application. This specific structure is not an essential part of the invention claimed herein and is

fully described and claimed in the parent 65 application Serial No. 1,004, and in other divisions thereof, to which reference is hereby made.

The following is a sample of the work 70 done by the above described mechanism:

3 124 60	75
182 300 17	
609 241 20	
316 406 32	
111 071 69	

I claim:

1. The combination of calculating mechanism, a rotatable platen, numeral types cooperative with said platen and calculating mechanism so as to print on a record sheet backed by said platen and according to the calculations of said calculating mechanism, means for rotating said platen to line-space 85 said record sheet, a plurality of ruling types, and means for causing said ruling types to be impressed concurrently with each other on said record sheet against said platen so as to produce ruling in relation to the numbers printed by said numeral types.

2. The combination of calculating mechanism, a platen, numeral types cooperative with said platen and calculating mechanism so as to print on a record sheet backed by 95 said platen and according to the calculations of said calculating mechanism, a plurality of horizontal ruling types, and means for causing said horizontal ruling types to be impressed concurrently with each other 100 on said record sheet against said platen so as to produce a horizontal line of ruling in relation to the numbers printed by said numeral types.

3. In a calculating machine, the combination of a plurality of accumulators, a plurality of type carriers, a plurality of numeral types mounted on each of said type carriers and operable thereby for printing on a record sheet according to the calculations of said calculating mechanism, and a plurality of horizontal ruling types, each mounted on a respective one of said type carriers, and means for effecting concurrent 110 impressing of all of said horizontal ruling 115 types so as to produce a horizontal line ruling in relation to the numbers printed by said numbers types.

4. In a calculating machine, the combination with a set of accumulators of operating 120 mechanism for causing said accumulators to effect accumulating of items, printing mechanism controllable by said operating mechanism for printing said items, a device for rendering said operating mechanism incapable of causing accumulating operation of said accumulators, and a controlling key 125 by the manipulation of which and the op-

- eration of said operating mechanism, said printing mechanism may be caused to print matter independent of control of said accumulators and said device may be rendered effective to prevent accumulating during such operation of said operating mechanism.
5. The combination of calculating mechanism, a platen, numeral types coöperative with said platen and calculating mechanism so as to print on a record sheet backed by said platen and according to the calculations of said calculating mechanism, a plurality of horizontal ruling types, means for causing said horizontal ruling types to be impressed concurrently with each other of said record sheet against said platen so as to produce a horizontal line of ruling in relation to the numbers printed by said numeral types, and means for rendering said calculating mechanism incapable of calculating in an operation of the machine in which said horizontal ruling types are impressed.
6. In a calculating machine, the combination of a plurality of accumulators; a platen; a plurality of sets of numeral types; a plurality of type carriers, each of said type carriers carrying a respective one of said sets of types, each set of types being correlated with a respective one of said accumulators; a plurality of series of numeral keys, each of said series of keys being correlated with a respective one of said type carriers and its respective set of numeral types and accumulator for determining what shall be accumulated by said accumulator and printed by said set of numeral types; a plurality of horizontal ruling types, each of said horizontal ruling types being mounted on a respective one of said type carriers; and a key for causing all of said horizontal ruling types to be brought into printing relation with said record sheet and platen and for causing said accumulators to be rendered incapable of accumulating during horizontal ruling operations of said machine.
7. In a key-controlled machine, the combination with a plurality of devices to be controlled; of a plurality of rows of keys; a plurality of differential stop mechanisms, one stop-mechanism for each of said rows of keys and controllable thereby for effecting differential control of the operation of a respective one of said devices; a special key operable for selectively controlling a plurality of said stop mechanisms for effecting control of their respective ones of said devices independently of the control of the keys of said plurality of rows of keys; and an operating mechanism for operating said plurality of devices, according to the control of said stop-mechanisms as determined by said plurality of rows of keys and as determined by said special key.
8. In a calculating machine, the combination of a plurality of sets of accumulators for accumulating separate series of items, a respective printing mechanism for each of a plurality of said sets of accumulators, operating mechanism common to for effecting registration of each of said sets of accumulators and printing by their respective printing mechanisms, and ruling mechanism operable by a single operation of said operating mechanism to print a rule line in relation to the matter printed by a plurality of said printing mechanisms.
9. In a calculating machine, the combination of a plurality of sets of accumulators for accumulating separate series of items; a plurality of sets of type-carriers, one set of type-carriers for each set of a plurality of said sets of accumulators; each of said type carriers being coöperative with a respective one of the accumulators of the respective set of accumulators; a plurality of sets of numeral types, each set of numeral types being mounted on a respective one of said type carriers; selecting mechanism for controlling operation of said sets of accumulators and printing by the numeral types on said type carriers; operating mechanism for operating said accumulators and types according to the control of said selecting mechanism; a plurality of horizontal rule types, one mounted on each type carrier of a plurality of said sets of type carriers; and a manipulative device coöperative with said operating mechanism for causing all of said horizontal ruling types to be brought to printing position and impressed for simultaneously printing ruling in relation to the items printed by the types of a plurality of said sets of type carriers.
10. In a printing mechanism, the combination of a plurality of separately shiftable printing types, a key the same manipulation of which always controls the shifting of the same plurality of said types, and operating mechanism for effecting printing by a plurality of said shifted types and at a single operation of said operating mechanism.
11. In a printing mechanism, the combination of a plurality of type-carriers each provided with a plurality of types, each of said type-carriers being movable to bring any one of a plurality of the types carried thereby into printing position irrespective of the movement of the other of said carriers; a plurality of manipulative devices operable for selecting singly and controlling printing by a plurality of said types of a plurality of said carriers; and manipulative means for selecting and controlling printing by a plurality of said types each of which is carried by a separate one of the carriers controllable by said plurality of manipulative devices, the same manipula-

tion of said manipulative means always effecting the selection and control of the same type.

12. In a printing mechanism, the combination of a plurality of type-carriers each provided with a plurality of types, each of said type carriers being movable to bring any one of a plurality of the types carried thereby into printing position irrespective of the movement of the other of said carriers; a plurality of manipulative devices operable for selecting singly and controlling printing by a plurality of said types of a plurality of said carriers; manipulative means for selecting and controlling printing by a plurality of said types each of which is carried by a separate one of the carriers controllable by said plurality of manipulative devices, the same manipulation of said manipulative means always effecting the selection and control of the same types; and means operable at a single operation for effecting printing of a plurality of selected types.

13. In a printing mechanism, the combination of a plurality of type-carriers each provided with a plurality of types, each of said type carriers being movable to bring any one of a plurality of types carried thereby into printing position irrespective of the movement of the other of said carriers; a plurality of keys operable for selecting singly and controlling printing by a plurality of said types of a plurality of said carriers; manipulative means for selecting and controlling printing by a plurality of said types each of which is carried by a separate one of the carriers controllable by said keys, the same manipulation of said manipulative means always effecting the selection and control of the same types; and operating means for effecting printing by the types under control of said plurality of keys or of said manipulative means and at a single operation of said operating means.

14. In a printing mechanism, the combination of a plurality of type-carriers each provided with a plurality of types, each of said type-carriers being movable to bring any one of a plurality of types carried thereby into printing position irrespective of the movement of the other of said carriers; a plurality of series of keys, one series for each of said type carriers and each key operable for selecting singly and controlling printing by a respective type of its associated carrier; manipulative means for selecting and controlling printing by a plurality of said types each of which is carried by a separate one of the carriers controllable by said plurality of series of keys, the same manipulation of said manipulative means always effecting the selection and control of the same types; and means operable at a

single operation for effecting printing by the types positioned under control of said plurality of series of keys or of said manipulative means.

15. In a printing mechanism, a plurality of types, a plurality of controlling members one for each of said types, and a key for controlling a plurality of said controlling members, whereby a single manipulation of said key will control printing by a plurality of said types, the construction and arrangement being such that the same plurality of types is always selected by the same manipulation of said key; and means operable at a single operation to effect printing by a plurality of the types selected by said key.

16. In a machine, the combination of setting keys, types a plurality of which are rule types, type carrying members carrying said types and controllable by said keys for positioning certain of said types to print, and a rule key for effecting the positioning of said members to bring said rule types into alinement for printing a line of ruling.

17. In a ruling mechanism, the combination with a platen of a plurality of type-carrying members, a plurality of ruling types each carried by a respective one of said type-carrying members, a stop device for controlling said members and a manipulative member operable to control said stop device for effecting ruling by a plurality of said ruling types.

18. In a printing mechanism, the combination of separately operable rule types, a key for controlling a plurality of said types, and a carriage mounted for horizontal movement relative to said types and adapted to carry a record sheet for receiving printing impression from said rule types in any one of a plurality of print-receiving positions of said carriage.

19. In a printing mechanism, the combination of a plurality of separately operable types, and a key for controlling printing by the same plurality of said types at every operation of said mechanism under control of said key.

20. In a printing mechanism, the combination of a plurality of type-carriers, a plurality of character types carried by each of said type-carriers, a plurality of character keys for controlling printing by said character types, a plurality of special types one mounted on each of a plurality of said type-carriers, a special key for controlling printing by a plurality of said special types, and a hand-controlled operation-controlling member a single operation of which can effect printing by a character type of each of a plurality of said type-carriers under control of said character keys or printing by a plurality of said special types under control of said special key.

21. The combination of a plurality of separately movable members, a plurality of ruling types one mounted on and movable with each of said members, and operating means operable at a single operation for effecting printing by a plurality of said ruling types.
22. A machine comprising an operating member, separately movable character printing types, and separately movable rule types a plurality of which may be impressed by a single operation of said operating member so as to print ruling in juxtaposition to the characters printed by said character printing types.
23. The combination with a platen of a plurality of printing segments arranged side-by-side, each provided with a plurality of printing types, one of said types of each segment being provided with a line ruling face; and means for alining the ruling types of all of said segments and for causing said
24. In a printing mechanism, the combination of a platen, a driver, a type-carrier, a rule type mounted on said type-carrier means for moving said type-carrier to bring said rule type into operative relation with said driver and said platen, and a means for actuating said driver to drive said rule type toward said platen.
25. In a key-controlled machine, the combination of a plurality of rows of keys movable from normal to operative position, a plurality of devices one for each of said rows of keys and controllable thereby, and a special key operable to control a plurality of said devices without effecting a control of said rows of keys.
